SAFETY LOCK FOR GRAIN ELEVATOR
MAN LIFTS

Fred E. Vane, Sublette, Kans.

Application April 13, 1949, Serial No. 87,304

2 Claims. (Cl. 187—92)

1

This invention relates to a safety lock for grain elevator man-lift.

The principle of a grain elevator man-lift involves a platform, which may be made of any material, which platform and frame thereof are large enough to accommodate a man standing on the platform. The platform frame is usually attached to a cable, of any material, which cable extends to the upper portion of the grain elevator and returns to the bottom of the elevator shaft when the lift is at the top of said shaft. A weight is attached to the cable, which counter-balances the platform weight of the lift and the operator riding thereon. This gives the operator an opportunity, by shifting a portion of his weight from the platform, to the stationary cable or rope, to either raise or lower himself and platform as he so desires.

Heretofore, different unsatisfactory means have been employed to retain the platform in a desired stationary condition. These common retaining means have often resulted unsatisfactorily, producing damage and possible serious injury to the operator.

Therefore, an object of this invention is to overcome unsatisfactory results and provide a positive means whereby injury to the platform or to the operator, or both, will be eliminated.

Another object of the invention is to prevent an accident, should the cable suspending the platform be broken, or if the cable should become inoperative for any reason.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a top plan view of a device constructed in accordance with the present invention, while

Figure 2 is a view in side elevation.

Figure 3 is an elevated view of the device, partly shown in longitudinal, vertical section and partly in side elevation.

Figure 4 is an enlarged, transverse, sectional view, taken on line 4—4, Fig. 2, and looking in the direction of the arrows.

Referring to the drawings, in which the preferred embodiment of this invention is illustrated, 1 designates the rail or guide for a man-lift. In this rail 1, at suitable intervals throughout its height, are placed metal sleeves 2 for the purpose hereinafter described.

2

On the platform 3, which is provided for the operator, is a primary angle bracket 4, which is suitably secured to said platform 3. A cylinder 5 is mounted on and extends through primary bracket 4, as shown. A threaded plug 6 extends partly into cylinder 5. A sliding bolt 7 extends through threaded plug 6 and the cylinder 5, Fig. 3. Within the cylinder 5 is a coil spring 7', this spring surrounding the sliding bolt 7. One end of coil spring 7' presses against the threaded plug 6 and its other end presses against washer 8, washer 8 being mounted on the sliding bolt 7, and held in position by the cotter pin 9. The cylinder 5 is fixed against movement on the primary bracket 4 by any ordinary means.

On platform 3 are two auxiliary angle brackets 10 which are arranged in parallel position and suitably secured in a fixed position upon platform 3 by any ordinary means. Extending through the auxiliary brackets 10 is a primary bolt 11. A flanged wheel 12 is fixedly secured to primary bolt 11. A foot pedal 13 is mounted on primary bolt 11, between two nut locks 14. By means of these nut locks the foot pedal 13 is fixedly mounted upon primary bolt 11 against independent movement upon said bolt. Therefore, when the operator places a foot upon said foot pedal 13 and presses down, the flanged wheel 12 will be rotated clockwise to cause chain 15 to be wound thereon. One end of chain 15 is fastened to the small screw bolt 16 and its opposite end is fastened to pin 17 that is attached to the sliding bolt 7. When the foot pedal 13 is pressed downwardly, as shown in dotted lines, Fig. 3, the coil spring 7' will be depressed by reason of the sliding bolt 7 being withdrawn from the metal sleeve 2 in which it may have been extended, whereupon the man-lift is free to move up or down in the elevator shaft, as the case may be.

The flanged wheel 12 has one of its flanges cut away, as at 18. A stop screw bolt 19, Fig. 4, extends through one of the angle brackets 10. The bolt 19 projects into the path of movement of the flanged wheel 12, working in the cut-away portion 18. When the device is in the position shown in Fig. 2, the stop screw bolt 19 will be engaging the upper end of the cut-away portion 18, as shown. Then when the device is in its releasing position, Fig. 3, the stop screw bolt 19 will be pressing against the lower end of the cut-away portion 18. By this efficient construction, the inner movement of sliding bolt 7 will be nicely controlled, while when the operator presses downwardly upon the foot pedal 13, unnecessary compression of the coil spring 7' will be elimi-

nated, since stop screw 19 will be engaging the inner end of the cut-away portion 18, as clearly shown in Fig. 3.

To securely mount stop screw bolt 19 upon the bracket 10, a lock nut 21 is placed on said bolt against one face of the bracket 10. Consequently, the stop screw bolt 19 is efficiently held in its operating position with respect to the flanged wheel 12.

If the man-lift accidentally moves in the elevator shaft, the sliding bolt 1 will enter the first metal sleeve that it registers with, thereby preventing the man-lift from moving any considerable distance, and consequently eliminating an accident. The operator can control the movement of the man-lift by manipulating the foot pedal 13. The objects set forth in the first part of the specification further point out the advantages of this invention.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In a device of the class described, the combination with a platform, of a pair of angle brackets mounted on said platform, a primary bolt extending through said angle brackets, a flanged wheel fixed to said primary bolt, said flanged wheel having one of its flanges partly cut away, a stop bolt on one of said brackets, said stop bolt extending into said cut-away part

of said flanged wheel, said stop bolt provided with a lock nut engaging the inner face of the angle bracket, a foot pedal fixedly secured to said primary bolt, a cylinder and means mounting said cylinder on said platform, a sliding bolt on said cylinder and means connecting said sliding bolt to said flanged wheel.

2. In a device of the class described, the combination with a platform, of an angle bracket mounted on said platform, a horizontal cylinder mounted on said angle bracket, said cylinder provided at one end with a threaded plug, a sliding bolt extending through said plug and through said cylinder, a coil spring on said sliding bolt, said spring within said cylinder, said spring bearing at its inner end against said threaded plug, a washer on said sliding bolt and pressing against the outer end of said coil spring, a wheel and means mounting said wheel on said platform, flexible means connecting said wheel and said sliding bolt, and a foot pedal connected to said wheel, whereby when said foot pedal is pressed downwardly, said sliding bolt will be drawn inwardly upon said cylinder.
